AIRCRAFT SERVICE STRUCTURE

Jack Jones, Wichita, Kans., assignor to Cessna
Aircraft Company, Wichita, Kans.

Filed Oct. 30, 1970, Ser. No. 25,732

Term of patent 14 years

Int. Cl. D25—03

U.S. Cl. D13—1

FIG. 1

FIG. 2

FIG. 3

FIG. 4

FIG. 1 is a perspective view of the aircraft service structure showing my new design;

FIG. 2 is a top plan view thereof; and

FIGS. 3 and 4 are side elevational views thereof.

I claim:

The ornamental design for an aircraft service structure, substantially as shown.
